Specification for Design.

Patented Feb. 21, 1922.

Application filed February 12, 1919. Serial No. 276,658. Term of patent 3½ years.

To all whom it may concern:

Be it known that I, WILLIAM CHERNOFF, a citizen of the United States, residing at Brooklyn, in the county of Kings, State of New York, have invented a new, original, and ornamental Design for a School Bag, of which the following is a specification, reference being had to the accompanying drawing forming a part thereof, wherein,

What I claim is—

The ornamental design for a school bag as shown.

In testimony whereof I have signed this specification in the presence of two subscribing witnesses.

WILLIAM CHERNOFF.
